(57) **CLAIM**

The ornamental design for a footwear upper, as shown and described.

DESCRIPTION

FIG. 1 is a perspective view of a preferred embodiment of the footwear upper;

FIG. 2 is a top plan view thereof;

FIG. 3 is a left side elevational view thereof;

FIG. 4 is a right side elevational view thereof;

FIG. 5 is a front elevational view thereof; and,

FIG. 6 is a rear elevational view thereof.

The broken line shown at the bottom of FIGS. 5 and 6 is provided only to show that the inner surface of the upper forms no part of the claimed design.
